[57] CLAIM

The ornamental design of a fishing lure, as shown and described.

DESCRIPTION

FIG. 1 is a front perspective view of the fishing lure of my design;

FIG. 2 is a top view thereof;

FIG. 3 is a bottom view thereof;

FIG. 4 is a left side view thereof, the right side view being a mirror image of the left side view;

FIG. 5 is a front view thereof; and,

FIG. 6 is a rear view thereof.

The broken lines shown in the drawing figures are for environmental purposes only and form no part of the claimed design.
